Primary Examiner — Leanne Was-Englehart(74) *Attorney, Agent, or Firm* — Gardner, Linn, Burkhardt & Ondersma LLP(57) **CLAIM**

The ornamental design for a woven cover for electrical conduit, as shown and described.

DESCRIPTION

FIG. 1 is a perspective view of a woven cover for electrical conduit showing our new design;

FIG. 2 is side elevation view thereof; and,

FIG. 3 is an end elevation view thereof, wherein the opposite end elevation is identical thereto.

The broken lines in the drawings are for the purpose of illustrating environmental structure and portions of the woven cover for electrical conduit that form not part of the claimed design. The woven cover for electrical conduit is shown with a symbolic break along its length in FIGS. 1 and 2. The appearance of any portion of the article between the symbolic break lines forms no part of the claimed design.

1 Claim, 2 Drawing Sheets(56)
